CLAIM

The ornamental design for a global positioning system receiver, as shown and described.

DESCRIPTION

FIG. 1 is a perspective view of a global positioning system receiver as viewed from an upper, right, front position, showing my new design;

FIG. 2 is a front view of the global positioning system receiver;

FIG. 3 is a plan view of the global positioning system receiver;

FIG. 4 is a rear view of the global positioning system receiver;

FIG. 5 is a right side view of the global positioning system receiver, while a left side view of the global positioning system receiver is a mirror image of the right side view; and, FIG. 6 is a bottom view of the global positioning system receiver.
